UNITED STATES PATENT OFFICE.

LEO F. ADT, OF ALBANY, NEW YORK.

EYEGLASSES.

1,150,845.

Specification of Letters Patent. Patented Aug. 24, 1915.

Original application filed February 14, 1908, Serial No. 415,808. Divided and this application filed May 11, 1912. Serial No. 696,590.

To all whom it may concern:

Be it known that I, LEO F. ADT, of Albany, in the county of Albany and State of New York, have invented certain new and useful Improvements in Eyeglasses; and I do hereby declare the following to be a full, clear, and exact description of the same, reference being had to the accompanying drawings, forming a part of this specification, 10 and to the reference-numerals marked thereon.

My present invention relates to eyeglasses and particularly to eyeglasses of the finger piece type and it has for its object to produce a simple, durable and efficient mounting of this nature in combination with a "stud" construction, namely, one in which the bridge is separate from and interchangeable with respect to the lens attaching portion.

Further objects are to provide an economical structure that may also be conveniently manipulated and to meet other requirements of a practical mounting.

To these and other ends the invention consists in certain improvements and combinations of parts, all as will be hereinafter more fully described, the novel features being pointed out in the claims at the end of the 30 specification.

In the drawings: Figure 1 is a front elevation of an eyeglass constructed in accordance with and illustrating one embodiment of my invention; Fig. 2 is a top plan view 35 thereof; Fig. 3 is a bottom plan view; Fig. 4 is a transverse central section through the bridge, showing one of the guard levers in side elevation; Fig. 5 is a section longitudinally of the bridge taken substantially on the line 5—5 of Fig. 2, on an enlarged scale; Fig. 6 is a section taken substantially on the line 6—6 of Fig. 5, and Fig. 7 is a detail perspective view of one of the guard levers and its spring.

Similar reference numerals throughout the several figures indicate the same parts.

This application is a division of my prior application entitled "Eyeglasses", Serial No. 415,808, filed February 14, 1908, which parent 50 application relates more particularly to the specific construction and arrangement of the guard levers and their springs, irrespective of the general nature of the support. Therefore, the same parts are shown here

only in an ancillary capacity and will be 55 but briefly described hereinafter.

In the practice of my invention, as shown in the present embodiment thereof, I provide a rigid, forwardly inclined, arched bridging portion 1, and a lens attaching portion at either end thereof that may, in general, be constructed very much as usual to comprise lens clips 2 and edge straps 3. The bridge, however, is made separate from and is detachable with respect to each lens attaching portion for the purpose of interchangeability, in order that particular bridges may be supplied for noses of particular proportions, as is known in the art, and to these ends one of the parts, preferably the lens attaching portion, is in each instance formed with substantially horizontally arranged seats, which in this instance, are in the form of boxes 4 opening toward each other to receive substantially horizontally arranged attaching arms or ends 5 extending outwardly from the other member, namely the bridge. Each seat or box is held to an attaching arm by an upright or vertically arranged fastener 6 which preferably is provided with an intermediate shoulder 7, a screw threaded portion 8 on one side of the shoulder and a bearing portion 9 on the other side of the shoulder. The screw threaded portion passes, preferably freely, through the arm 5 on the bridge in each instance and engages the screw threaded walls of an opening 10 in the bottom of the box 4, this end of the fastener also projecting beyond or below the box for a purpose hereinafter described. As the fastener is applied, the shoulder 7 thereon draws the attaching arm 6 of the bridge and the seat or box together, and to this end the opening in the upper wall of the box, which is in alignment with the lower opening 10, is enlarged to permit the shoulder to preferably directly engage the attaching arm. The bearing portion 9 on the fastener above the shoulder 7 projects from the box 4 and is surmounted by a head 11 providing another shoulder spaced from the box, and it is between the latter and this shoulder that the finger piece guard lever is retained to turn upon the bearing portion 9 as a pivot. These guard levers 12, which will be found to be more carefully described in my prior application

above referred to, are arranged to extend from front to rear of the mounting, as usual, to operate in a substantially horizontal plane, and are fitted with nose engaging portions 13 at their rear ends and finger pieces 14 at their forward ends. At an intermediate point, each is provided with a notch or open bearing 15 adapted to coöperate with the bearing portion 9 of the fastener 6 and these and adjacent parts are so proportioned as to permit the guard lever, in each instance, to be applied to or removed from its support in a lateral direction by 10 tilting it and sliding it under or from beneath the head 11 of the fastener in a manner fully described in several of my prior applications and patents, so that in the present embodiment of this invention it is not required to remove the fastener and release, even partially, the bridge and lens attaching portions in order to release or remove the guard lever. The finger piece 14 of each lever is, in the present instance, constituted by a loop in the material of the lever formed by an arm that proceeds downwardly and rearwardly and finally merges into the outer convolution of a flat spiral coiled spring 16 which is thus formed integrally therewith in this embodiment. 15 There is one of these springs, of course, for each guard lever that operates to position its nose engaging portion against the nose and aside from being carried by its guard lever and detachable therewith, it is centered against lateral movement by the lower or reduced projecting end of the fastener 6 before described, as clearly shown in Fig. 5, the spring being on the opposite side of the supporting portion of the mounting from 20 the guard lever. The inner end 17 of the spring is extended from the inner convolution across the coil and coöperates with a stationary part provided, in the present instance, by a depending hook or projection 18. 25 Of course, I do not wish to limit myself to the use of the particular spring and guard, shown in my prior application, in connection with the supporting structure forming the subject matter of this application as other springs and guards of a widely different character may be employed, with good results, in such "stud" construction. Such details are described herein only for the purpose of showing a complete eyeglass and one mode of practising the invention here involved.

I claim as my invention:

1. In an eyeglass mounting, the combination with a lens attaching device and a bridge, of a connection between them embodying a substantially horizontal seat on one of said parts, a substantially horizontal arm on the other of said parts and a fastener having a shoulder intermediate its ends engaging one part for drawing the

parts together, a screw portion on one side of the shoulder threaded into the other part only, and a bearing portion on the other side of the shoulder, and a finger piece nose guard lever turning on the bearing. 70

2. In an eyeglass mounting, the combination with a bridging portion and a lens attaching device, of means connecting them comprising an arm on one of said parts, a horizontally arranged box on the other of said parts, and a screw fastener having a shoulder engaging one part and threaded into the other part, only, for drawing the box and the arm together and also having a bearing portion projecting from one side of the box and a head; and a finger piece guard lever mounted to turn on the bearing portion in engagement with the box and the head. 75

3. In eyeglasses, the combination with a lens attaching device and a bridge, of a fastener threaded into one of said parts to extend freely through the other and having a shoulder engaging the outer side of the latter, and a finger piece nose guard lever turning on the fastener beyond the shoulder. 80

4. In eyeglasses, the combination with a lens attaching device and a bridge, of a fastener having a reduced portion threaded into one of the parts and extending freely through the other and having its enlarged portion bearing against the latter and projecting outwardly beyond the parts and terminating in a head, of a nose guard turning on the enlarged portion beneath and in engagement with the head being confined between the latter and one of the first mentioned members. 95

5. In eyeglasses, the combination with a lens attaching portion and a bridging portion separate therefrom, of a fastener for securing said parts together having portions projecting from opposite sides of both of them, a pivoted finger piece guard lever mounted on one such projecting portion and a spring for positioning the guard coiled about the other. 100

6. In eyeglasses, the combination with a lens attaching portion and a bridging portion separate therefrom, of a fastener for securing said parts together to form a support and having portions projecting from opposite sides of both of them, a shoulder on one such projecting portion spaced from the support and a finger piece guard lever and an actuating spring therefor respectively, mounted on the projecting portions of the fastener with one of them retained between the shoulder of the fastener and the support. 115

7. In eyeglasses, the combination with a support comprising a lens attaching device and a bridge, of a fastener for securing the lens attaching device to the bridge, project- 120

130

ing upwardly, a finger-piece nose guard turning on the upwardly projecting portion of the fastener, and a spring carried by the guard and having one end detachably interlocked with the support.

8. In eyeglasses, the combination with a lens attaching device and a bridge separate therefrom, of a fastener extending through the parts to rigidly secure them together and having a head spaced therefrom and lying to one side of both and a finger-piece nose guard pivoted to turn between the head and one of the parts.

9. In eyeglasses, the combination with a lens attaching device and a bridge, of a fastener extending through the parts and having a shoulder engaging the outer side

of one of them and a bearing projecting beyond the shoulder and a finger-piece nose guard turning on the bearing.

20

10. In eyeglasses, the combination with a lens attaching device and a bridge, of a fastener extending through the parts to project to one side of both and having spaced shoulders on such projecting portion one of which engages one of the members, of a finger-piece nose guard confined between the other shoulder and said member and turning on the projecting portion of the fastener.
